CIPHER DEVICE

Carlos A. Hepp, Englewood, N. J., assignor of fifty
per cent to Philip G. Hilbert, Astoria, N. Y.

Application March 13, 1951, Serial No. 215,297

2 Claims. (Cl. 35—3)

1

This invention relates to a cipher device.

An object of this invention is to provide a cipher device which is compact in form, may be readily carried about one's person and is adapted to be manipulated with a minimum amount of effort to cipher or decipher a code message.

Another object of this invention is to provide a device of the character described in the form of an annular member which may be worn on the wrist in simulation of a bracelet or the like, such member carrying endless cipher bands and disposed in side by side relation on the outer surface thereof whereby selected indicia carried on the outer surface of the bands may be brought into predetermined relation to each other in order to cipher or decipher a code message, upon rotating the bands relative to the member.

A further object of this invention is to provide a cipher device which includes an annular support in simulation of a bracelet, a pair of endless cipher bands rotatably mounted on the outer surface of the support in side by side relation, together with an endless cover band overlying the cipher bands and formed with openings through which selected indicia appearing on the cipher bands are visible, the cover band harmonizing in appearance with the support to give an overall ornamental appearance to the device, yet being readily manipulated to allow code messages to be ciphered or deciphered with a minimum amount of effort.

Still another object of this invention is to provide a cipher bracelet carrying endless cipher bands in rotatable relation thereto, such bands being readily removed from the bracelet and replaced with other bands whereby to readily and quickly vary possible combinations of ciphers to be used in ciphering or deciphering a code message.

Other objects of this invention will in part be obvious and in part hereinafter pointed out.

In the accompanying drawing:

Fig. 1 is a perspective view of the device embodying the invention;

Fig. 2 is a sectional view taken on the line 2—2 of Fig. 3;

Fig. 3 is a top plane view of a portion of the device;

Fig. 4 is a side view thereof showing a modification;

Fig. 5 is a top plan view thereof.

The device embodying the invention comprises essentially an annular member formed of suitable flexible or semi-flexible material and of such dimensions as to make the same suitable for

2

use as a bracelet which is to be worn on the wrist or the like. Such member provides a support for a pair of endless cipher bands disposed on the outer surface thereof in side by side relation for relative rotation. Each of the cipher bands bears on the outer surface thereof circumferentially spaced indicia whereby upon rotation of the bands, selected combinations of indicia may be brought into registering relation in order to cipher or decipher a given code message.

Furthermore, in order to emphasize the bracelet effect of such device, an endless cover band is rotatably mounted over both cipher bands to substantially conceal the same from view. The cover band is formed with openings disposed in a manner to render visible the selected indicia on the cipher bands, upon suitable manipulation of the cipher and cover bands.

Referring in detail to the drawing, 10 designates a cipher device embodying the invention. The same comprises an annular member 11 of such dimensions as to make the same suitable for wearing on the wrist or the like. The member 11 may be formed of plastic, paperboard or other suitable flexible or semi-flexible material and is provided on the outer surface thereof with a shallow groove 12 extending circumferentially thereof. The groove 12 is located intermediate the lateral edges of member 11, thus leaving laterally spaced, circumferentially extending shoulders 13.

Rotatably mounted on member 11 and disposed within groove 12 thereof, are a pair of endless cipher bands 14, 15 in side by side relation. The cipher bands may be formed of a flexible material such as plastic or the like, which is somewhat extensible whereby the same may be stretched, passed over the shoulders 13 on member 11 and properly located in groove 12 in their normal, retracted condition. Each of the bands is imprinted or otherwise provided on the outer surface thereof with circumferentially spaced indicia such as letters, numbers, symbols or combinations thereof.

In order to allow each of the cipher bands 14, 15 to be readily rotated in respect to member 11, the bands are provided with lips 16, 17, respectively. The lips project upwardly and slightly above the outer surface of shoulders 13 of member 11, extending from the outer edges of the respective cipher bands. It is apparent that the bands 14, 15 may be readily rotated relative to each other to bring into registry any desired combination of indicia on the respective bands, merely by moving lips 16, 17.

There is further provided an endless cover band 18 which is also adapted to be rotatably mounted on member 11, being disposed in groove 12 and overlying the cipher bands 14, 15 to substantially conceal the same from view. The band 18 is of a transverse dimension substantially equal to the width of groove 12 less the thickness of lips 16, 17. The thickness of band 18 is such that combined with the thickness of the cipher bands, its outer surface is substantially flush with the shoulders 13 on member 11. The cover band 18 is also formed of a somewhat elastic, plastic material or the like, and may be colored, ornamented or otherwise treated on its outer surface to harmonize and complement colors or designs which may be applied to the outer surfaces of shoulders 13.

The cover band 18 is formed with a pair of inconspicuous openings 19, 20 which may be in side by side relation and adapted to expose to view registering indicia appearing on the cipher bands 14, 15, respectively. When wearing the device 10 on the wrist, the member 11 may be turned so that the openings 19, 20 are on the underside of the wrist and more or less concealed from view, the lips 16, 17 also being turned to a similar position, thereby allowing the device to simulate an ornamental bracelet or the like. When the device is to be used for cipher purposes, the same may be manipulated either on or off the wrist of the wearer. In either case, a predetermined code combination of indicia appearing on the cipher bands 14, 15, is agreed upon. Thus, assuming that the indicia is in the form of letters of the alphabet, as indicated in Fig. 3, and further that the prearranged code is A-J, then the bands 14, 15 are turned by means of lips 16, 17 until the desired combination of letters appear in the openings 19, 20 of the cover band 18. Thereafter in order to encipher or decipher a message, it is only necessary to rotate the cover band 18 to bring into registry the desired combinations of indicia. Thus, as shown in Fig. 3, wherever B appears in the cipher message, it actually stands for K, while Z stands for I; Y stands for H, etc.

It is understood that the exact sequence of letters, numbers, symbols or the like, may be different on a number of auxiliary cipher bands which may be used to replace the cipher bands in use, thereby multiplying the possible combinations of codes. The bands are readily interchanged by slipping the cover band from the member 11 and then removing the cipher bands 14, 15 and replacing the same with other cipher bands and finally replacing the cover band. The circumferential dimensions of the cipher and cover bands may be readily determined to allow free rotation of the respective bands on member 11.

To accentuate the ornamental effect of the device when the same is worn on the wrist, the manually operable means for rotating the cipher bands 14, 15 may be in the form of ornamental members 16a, 17a extending from lips 16, 17, respectively, as shown in Fig. 5. In this case, the members 16a, 17a, do not have to be concealed from view and in fact, are colored or formed to blend with the ornamental effect of the bracelet as a whole.

It is also understood that indicia other than letters, such as numbers, symbols and combinations thereof, may be used in any desired arrangement on the cipher bands, whereby information may be suitably enciphered and deciphered in accordance with a prearranged code. Also, each cipher band may bear more than one row of circumferentially spaced indicia, the cover band being provided with the appropriate number of openings located in proper position. Furthermore, such openings may be displaced circumferentially of each other to provide other combinations of visible indicia.

There is thus provided a cipher device which may be used as a bracelet and in which the several objects of the invention are achieved.

As various possible embodiments might be made of the above described invention, and as various changes might be made in the embodiments set forth, it is to be understood that all matter herein set forth or shown in the accompanying drawing, is to be interpreted as illustrative and not in a limiting sense.

Having thus described my invention, I claim as new and desire to protect by Letters Patent:

1. A cipher device comprising an annular, flexible supporting member formed on its outer surface with a shallow groove extending circumferentially thereof, a pair of cipher bands rotatably disposed within said groove in side by side relation and an endless cover band overlying said cipher bands and substantially concealing the same from view, said cover band being formed with openings for rendering visible selected indicia appearing on the respective cipher bands.

2. An ornamental bracelet comprising an annular member formed with a circumferentially extending shallow groove on the outer surface thereof and providing circumferentially extending marginal shoulders thereon, an endless cover band located within and substantially spanning the groove and harmonizing in appearance with the shoulders of said member, said cover band being formed with a plurality of openings, and a pair of endless cipher bands disposed between the bottom of said groove and the inner surface of said cover band, said cipher bands being disposed in side by side relation and bearing indicia on the outer surfaces thereof visible through the openings in said cover band, and means on each of said cipher bands for manually rotating said band relative to said member and said cover band.

CARLOS A. HEPP.
